Attorney

UNITED STATES PATENT OFFICE

JOHN K. HARFORD, OF LEWISTON, IDAHO

CLOSURE FASTENER

Application filed July 8, 1929. Serial No. 376,610.

My present invention relates to an improved closure fastener which, while adapted for use in various ways is particularly designed for use with the caps of radiators of 5 automotive vehicles, gasoline tanks, &c. The closure is of that type utilizing a key and lock device with rotary spindles or fastening devices that co-act with a stationary part or member to which the closure is fastened. The 10 primary object of my invention is the provision of a device of this character that is comparatively inexpensive in cost of production; simple in construction and operation; and which is effective in the performance of 15 its required functions.

The invention consists in certain novel combinations and arrangements of parts as will hereinafter be more fully pointed out and claimed. In the accompanying drawings I 20 have illustrated one complete example of the physical embodiment of my invention wherein the parts are combined and arranged in accord with the best mode I have so far devised for the practical application of the 25 principles of my invention.

Figure 1 is a perspective view of the device, showing the key in operative position. Figure 2 is a view partly in elevation and partly in vertical section, as at line 2—2 of Figure 3. 30 Figure 3 is a view partly in elevation and partly in section as at line 3—3 of Figure 2, with one of the duplex fasteners released and the other fastener locked. Figure 4 is a sectional view as at line 4—4 of Figure 3.

In order that the general arrangement, 35 utility of the device, and relation of parts may readily be understood I have indicated by the numeral 1 a portion of a tank or other receptacle that is to be closed after filling, 40 and the tank is provided with a nipple 2 that is fashioned with a horizontal, interior, annular flange 3.

The filling nipple is normally closed by the 45 use of a cap 4 of cylindrical shape to fit over the nipple, and an annular ring or gasket 5, interposed between the flange 3 and the cap, provides a leak-proof joint between the nipple of the tank and the cap or closure.

The cap is fashioned with an upwardly 50 projecting lock-head 6 having a central key-

hole 7 for the flat key 8, and the key is designed to co-operate with a pair of pawls 9 and 10 that are spaced at different levels and movable in lateral recesses or sockets 11. By turning the key in one direction the two pawls 55 are turned to locked position and a turn on the key in the opposite direction releases the pawls from locked position.

The locking pawls are designed to co-act with a pair of duplex vertically arranged, 60 parallel spindles 12 and 13 that are supported in the head at opposite sides of the key or the key-hole, and these spindles are permitted to have both a rotary motion and a vertically reciprocable motion in the head. 65 On their upper ends, exterior of the lock-head, the spindles are provided with knurled knobs 14 and between the knobs and the upper face of the head are interposed springs 15 coiled about the spindles. The springs normally bend to lift and hold the spindles in their uppermost positions, but the spindles are depressible against the tension of the springs when the cap is to be removed after 70 the key 8 is turned to release the pawls 9 75 and 10.

At their lower ends the spindles are provided with horizontally extending latch-lugs or latches 16 and 17, which are rigidly secured on the spindles by means of nuts 18 80 threaded on ends of the spindles below the latches. When the closure is in locked position these latches extend outwardly from the spindles and engage against the underside of the annular flange 3 or the top of the tank, as 85 shown, and the springs 15 tend to hold latches 16 and 17 in frictional contact with flange 3, or tank, as in dotted lines Figure 3. When the closure is unlocked or the cap removed from the nipple, the latches are turned inwardly toward the center line of the cap, one of which is shown in full lines Figure 3, in order that the cap may be removed without encountering any obstructions.

Each of the spindles is provided with a 95 flat face 19 extending longitudinally thereof and the two pawls 9 and 10 of the lock device co-act with these faces to prevent turning of the spindles that would release the catches or latches from the flange. After the key is 100

turned to withdraw these pawls from contact with the flat faces 19, it will be apparent that the spindles may be depressed to full line position, in Figure 3, and turned inwardly, and by means of an annular groove 20 on each spindle that co-acts with a retaining lug 21, the spindle may be held in depressed and fastened position. The retaining lug is a metal plate fastened to the lower inside face of the lock head by screws 22 and the ends of the plate are used as lugs for engaging in the groove. When the flat face 19 of the spindle is turned to position opposite the lug, of course the latter has no contact with the spindle and therefore the latter may be reciprocated. By turning the spindle 13 in Figure 3 through an arc of 180 degrees, the flattened face 19 is brought opposite to the retaining lug 21, and the spring 15 is then free to lift the latch 16 into contact with flange 3, or shoulder 23. Then the key 8 is turned to project the pawl 9 against the flat face 19 of the spindle, thereby preventing rotation of the spindle, and depression of the spindle is prevented by the presence of the shoulder 19' positioned just above the pawl 11.

By this duplex arrangement of the spindles the cap is rigidly retained in position on the nippel, but the cap may readily be unlocked by the use of the key and then the cap is unfastened and removed with facility, when required.

Having thus fully described my invention, what I claim as new and desire to secure by Letters Patent is:—

1. In a closure device the combination with a cap and its head, of a rotatable and depressible, spring-pressed spindle supported in the head, a catch rigid with the spindle for engagement with a stationary member, means for locking the spindle against rotation when in closed position; and means for retaining the spindle against reciprocation when in open position.
2. The combination with a cap and its lock-head and a lock in the head, of a rotatable, depressible, spring-pressed spindle having a fastening catch at one end, said spindle having a flat face for co-action with the lock, and an annular groove, and a fixed retaining lug for co-action with the groove.
3. The combination with a cap, its lock head and a lock in the head, of a retaining plate forming lugs in the cap, a pair of spring pressed, depressible spindles having annular grooves for co-action with said lugs, fastening latches on said spindles for co-action with a stationary member, and flat faces on the spindles for co-action with the lock as described.

In testimony whereof I affix my signature.
JOHN K. HARFORD.
